UNITED STATES PATENT OFFICE.

JERRE MCPHAIL BOWLES, OF ATLANTA, GEORGIA, ASSIGNOR OF ONE-THIRD TO
GEORGE MOSES BARUDAY, OF WASHINGTON, DISTRICT OF COLUMBIA.

MARINE PROPULSION.

1,401,036.

Specification of Letters Patent. Patented Dec. 20, 1921.

Application filed July 22, 1921. Serial No. 486,764.

To all whom it may concern:
Be it known that I, JERRE MCPHAIL BOWLES, a citizen of the United States, residing at Atlanta, in the county of Fulton and State of Georgia, have invented certain new and useful Improvements in Marine Propulsion; and I do hereby declare the following to be a full, clear, and exact description of the invention, such as will enable others skilled in the art to which it appertains to make and use the same.

This invention relates to means for utilizing the energy developed by the rolling motion of a marine vessel to propel or assist in propelling the vessel.

Its object is to provide suitable propeller vanes which automatically adjust themselves as the vessel rolls and so utilize the resistance of the water to advance the vessel; other objects are to enable the propeller to be withdrawn into the hull when desired; to limit the movements of the propeller without the use of stops on the hull; to limit adjustably the angles to which the propeller vanes may swing; to improve the design of the propeller vanes and to otherwise improve the details of structure as more fully set forth in the ensuing description, illustrated in the drawings and defined in the appended claims.

In the accompanying drawings:

Figure 1 is a fore and aft section of as much of a marine vessel as is necessary to illustrate my invention;

Fig. 2 is a transverse section of a fragment of a hull disclosing my improvement in place;

Fig. 3 is a diagrammatic view of two propeller vanes, the associated stop mechanism, and the mechanism for raising and lowering said propeller vanes;

Fig. 4 is a top plan view of a propeller vane;

Fig. 5 is a diagrammatic elevation of a vessel showing the propellers extended;

Fig. 6 is a similar view showing the propellers retracted;

Fig. 7 is a bottom plan view of the vessel shown in Fig. 6;

Fig. 8 is an elevation of a peculiar form of set screw used to fix the length of the stop link.

Like reference characters indicate like parts throughout the several views.

In the embodiment illustrated 1 indicates the hull of a marine vessel, 2 the keel thereof and 3 the main deck.

As shown in Figs. 5, 6 and 7 the propelling mechanism is centrally located substantially amidship. Referring to Fig. 1, characters 4 and 4^a indicate shaft wells extending perpendicularly substantially through the hull. The lower portions of each shaft well, as at 5 and 5^a, are cut away on the after sides and open into propeller-wells 6 and 6^a, the propeller-well 6 opening through the bottom into the sea on the port or left hand side of the keel 2 and the propeller-well 6^a opening into the sea on the starboard or right hand side of the keel. By this disposition of the shaft wells and propeller wells, cutting or modifying the structure of the keel is unnecessary. In each of the shaft wells there is an upper circular bearing 7 secured by pins 7^a or otherwise, firmly at the upper end of said shaft well at or above the surface of the main deck 3. At the lower end or bottom of each shaft well and secured to the forward wall thereof is a half bearing 8, while disposed between the said bearing 7 and half bearing 8 is a second half bearing 9 suitably secured to the after side of each shaft well at the lower end of the complete cylindrical portion of said wells. Journaled perpendicularly in each shaft well and engaging the bearings 7, 8 and 9 is a propeller shaft 10 or 10^a. These shafts are adapted to rotate freely in the bearings 7, 8 and 9 and to slide longitudinally therein so as to adjust their position vertically. The shafts 10, 10^a are preferably tubular in order that adequate rigidity and strength may be secured without excessive weight. Rigidly secured to the after side at the lower end of each shaft 10, 10^a is a propeller 11, 11^a.

These propellers are of great strength each consisting, preferably, of an open metallic frame work to which are riveted metallic plates 12 as shown. As indicated in Figs. 1 and 4 it is preferred to make the propeller vane of rudder-like formation, wider at the lower end than at the upper end. It is also preferred to taper the sides of the propeller vanes from the front toward the rear, the taper extending symmetrically at any horizontal plane on each side with respect to the central fore and aft vertical plane of the vane. It is furthermore preferred to vary

the pitch of the propeller vanes or the inclination of the sides with respect to the central plane from top to bottom of said vane. As shown in Fig. 4 the sides of the propeller vanes at the top are nearly parallel while the said sides gradually converge more and more toward the central plane from front to rear proceeding downward. The purpose of this variation in taper is to secure the most effective action of the water upon said vane, as the arc of movement of the lower portion of the vane during the rolling motion of the vessel is greater than the arc of movement of the upper portion thereof.

In order to limit the oscillation of the propeller vanes during the rolling movement of the vessel I prefer the following mechanism: At the upper end of the shaft 10 is secured a crank 13 which projects from shaft 10 from the same side as the propeller 11. Secured to the upper end of the shaft 10^a is a crank 13^a which projects from the side of said shaft 10^a opposite that of the propeller vane 11^a. As the propeller vanes are not exactly on the midship fore and aft plane, but are on opposite sides of the keel, the cranks are disposed at slight angles to the propeller vanes, and in such relation to said vanes that, when said cranks are in alignment with each other, so that a line connecting the centers of shafts 10 and 10^a at the points of connection of said cranks thereto bisects said cranks longitudinally, each propeller vane then rests in a fore and aft plane, the stop links then extending in alignment with said cranks at an acute angle to the keel. Connected to the crank pin 14 on the crank 13 is a slotted link section 15, the pin 14 engaging in the slot of said link section. A similar link section 15^a is shown similarly connected to the crank pin 14^a of the crank 13^a. The outer ends of said link sections 15 and 15^a are threaded oppositely, the section 15 being shown in the illustration as having a right hand thread and the section 15^a being shown as having a left hand thread. Threaded into the ends of said link sections 15 and 15^a is a screw rod 16 having right hand threads at one end and left hand threads at the other. Between these threads there is preferably mounted a hand wheel 17 by which the threaded rod may be rotated. In order to secure the threaded rod against rotation a pointed set screw 18 is threaded into the side of each link so that its point will engage in the spiral groove of the threaded rod. By means of this construction it will be seen that if the set screws 18 are released and the threaded rod is rotated by means of the hand wheel to the right, (as shown in Fig. 3), the links 15 and 15^a will be drawn together and when they have been so drawn together as far as is possible the vanes 11 and 11^a cannot oscillate to any material ex-

tent and will extend substantially fore and aft of the vessel. By revolving the hand wheel 17 to the left (as shown in Fig. 3) the link connection between the cranks 13 and 13^a will be extended, the slots providing for a certain amount of lost motion, and the said vanes 11 and 11^a may be oscillated freely in one direction until the crank pins 14, 14^a engage the outer ends of the slots in said links 15, 15^a whereupon the said vanes can oscillate no farther in that direction. A reverse oscillation may take place which will be stopped in the same manner when the vanes have reached the other side of the center of the fore and aft perpendicular planes of the vessel at the same angle at which they were stopped in the said first oscillation. It will be seen that by this construction the extent of oscillation of the vanes may be determined, or oscillation of the vanes may be substantially prevented, and that the hull receives no shock from the oscillating vanes. The extreme length of the stop link, it will be seen, is slightly less than the distance between centers of shafts 10, 10^a, so that said link can in no case permit a movement of the vanes through an arc of more than 180°.

The propeller vanes may be raised or lowered within limits in order to assist in steadying the vessel or to change their respective arcs as may be desired according to the character of the seas and the extent of rolling. To effect the vertical adjustment of the propellers 11 and 11^a cables, preferably of steel, 20 and 20^a, are attached to the shafts 10 and 10^a preferably at a point between the half bearing 8 and the half bearing 9, as said shafts are disposed when the propellers are fully projected as shown in Fig. 1. In the present embodiment the cable ends are attached to pins 21, 21^a which project through said shafts 10 and 10^a and forward into the wells 5 or 5^a. These cables pass upward in the wells and over sheaves or guide rolls 22 on the forward side of the wells and thence to a windlass having suitable winding drums one for each cable. Each winding drum preferably consists of a pair of disks 23 secured to the windlass shaft and spaced apart a distance equal to the diameter of the cable so that during the winding of the cable one turn will rest on top of the other between said disks. Upon the windlass shaft there may be a worm wheel 24 with which engages a worm 25 secured to a vertical shaft 26 upon the upper end of which is a hand wheel 27. Gearing of the type shown is self-locking and it is only necessary to turn the wheel 27 in the proper direction and to the desired extent to raise or lower the propeller vanes 11, 11^a as desired and the said vanes will then remain in said position. To avoid accidental vertical displacement, however, of the 130

- said vanes I may use a set screw 28 to engage the shaft 26 and prevent accidental movement thereof. In the construction illustrated, by turning the hand wheel 27 in a counterclockwise direction, the vanes 11 and 11^a may be elevated to any extent or may be withdrawn entirely into the wells 6 and 6^a. By rotating the hand wheel 27 in a clockwise direction the said vanes may be lowered.
- 10 The half bearings 8 exert no obstruction to the movements of the propeller vanes 11 and 11^a into the wells and, as the resistance of the water in the rolling of the ship tends to thrust the lower ends of said shafts 10 and 10^a forward against said half bearings 8, there is no danger of the shafts becoming disengaged from said half bearings. The half bearings 9 permit the shaft 10 or 10^a to rise freely without offering any obstruction to the pins 21, 21^a or to the passage of the hoisting cables 20, 20^a. As the shafts 10 and 10^a have a tendency to buckle in a rearward direction where they engage the half bearings 9, said half bearings are effective 20 to retain the shafts in position. In order to avoid chafing of cable 20^a on the forward well 4, it may be led over a sheave 29 mounted on one side of said well 4, as shown in Fig. 3.
- 30 The propeller vanes, when projected beneath the hull, will be operative to control the vessel or to assist in propelling the vessel provided the said vessel has any rolling motion. Assuming that the adjustable link stop mechanism has been set to allow a suitable limited oscillation of the vanes 11 and 11^a it will be apparent that as the vessel rolls to port the vanes 11 and 11^a will move bodily in the opposite direction and 35 the resistance of the water against them will cause them to oscillate to port about the axes of the shafts 10, 10^a. The pressure of the water against the obliquely arranged vanes will then resist the rolling motion of 40 the vessel and exert pressure tending to force it forward on substantially the same principle as that of the screw propeller. When the vessel rolls to starboard the vanes will similarly be oscillated bodily to starboard 45 and the resistance of the water on the other side will produce a corresponding forward impulse, as before. Variations of the effects of the propellers may be produced by projecting them more or less below the bottom. They are effective in checking excessive rolls as well as of utilizing the otherwise wasted energy of the rolling movement to propel the vessel.
- Having described my invention in the 50 form now best known to me what I claim and desire to secure by Letters Patent is:
1. In marine propulsion mechanism, a hull, a propeller vane directly pivoted in an upright position to bearings fixed to said 55 hull, said vane being disposed directly below the bottom of said hull and means for limiting the oscillation of said propeller vane.
2. In marine propulsion mechanism, a hull, bearings disposed perpendicularly in the hull, a shaft journaled in said bearings so as to oscillate about its longitudinal axis, said shaft having its lower end projecting below the hull, a propeller vane having one edge secured to the shaft wholly below the hull, and means for limiting the oscillatory movements of the shaft.
3. In marine propulsion mechanism, a hull, bearings disposed perpendicularly in the hull, a shaft journaled in said bearings, said shaft having its lower end projecting below the hull, a propeller vane having one edge secured to the lower end of the shaft, wholly below the hull, means for limiting the oscillatory movements of the shaft, and means for elevating or lowering the shaft.
4. In marine propulsion mechanism, a hull, bearings disposed perpendicularly in the hull, a propeller well opening into the bottom of the hull, a shaft journaled in said bearing, said shaft having its lower end projecting below the hull, a propeller vane having one edge secured to the lower end of the shaft, means for limiting the oscillatory movement of the shaft, and means whereby the shaft and propeller vane may be elevated so as to house the propeller vane in the well or lowered to project it therefrom.
5. In marine propulsion mechanism, a hull, a shaft well arranged perpendicularly in said hull, bearings in the shaft well, a shaft journaled in said bearings, said shaft having its lower end projecting below the hull, a propeller vane having one edge secured to the lower end of said shaft, a hoisting device, a cable guide, and a cable extending from the hoisting device over the cable guide into the shaft well, the end of the cable being secured to the shaft in the shaft well.
6. In marine propulsion mechanism, a hull, a shaft well arranged perpendicularly in said hull, bearings in the shaft well, a shaft mounted in said bearings, said shaft having its lower end projecting below the hull, a propeller vane having one edge secured to the lower end of said shaft, a hoisting device comprising a drum shaft having a worm wheel secured thereon, a worm secured to an operating shaft engaging the worm wheel, and a flexible cable connected to the drum and to said shaft within the shaft well.
7. In marine propulsion mechanism, a hull, a shaft well arranged perpendicularly in said hull, a propeller well communicating with the shaft well at its front end, said propeller well opening through the bottom of the hull, a cylindrical bearing at the

upper end of the shaft well, a half bearing secured to the forward side of the lower end of the shaft well, a shaft journaled in said bearing, a propeller vane having one edge secured to the lower end of the shaft, means for limiting the oscillatory motion of the shaft, and hoisting means for raising or lowering the shaft and propeller vane.

8. In marine propulsion mechanism, a hull, a shaft well arranged perpendicularly in said hull, a propeller well having its front end communicating with the shaft well, said propeller well opening through the bottom of the hull, a cylindrical bearing at the upper end of the shaft well, a half bearing secured to the forward side of the lower end of the shaft well, an intermediate half bearing secured to the after side of the shaft well, a shaft journaled in said bearings, a propeller vane having one edge secured to the lower end of the shaft, means for limiting the oscillating motion of the shaft, a hoisting means comprising a cable secured to the shaft at a point between said half bearings when the shaft is in lowered position for raising or lowering the shaft and propeller vanes.

9. In marine propulsion mechanism, a hull, shafts journaled perpendicularly in said hull, with their lower ends projecting below the hull, a propeller vane having one edge secured to the lower end of each shaft, and a link connection between said shafts so as to permit independent oscillation of each, but constructed to limit the oscillation of said shafts in each direction.

10. In marine propulsion mechanism, a hull, oscillatory shafts journaled therein, propeller vanes secured to said shafts and extending in the same direction therefrom, a crank arm secured to each shaft, the crank arm on one shaft extending in a direction opposite that on the other shaft, and a link having a lost motion connection between the said crank arms for limiting the oscillation thereof.

11. In marine propulsion mechanism, a hull, oscillatory shafts journaled therein, propeller vanes secured to said shafts and extending in the same direction therefrom, a crank arm secured to each shaft, the crank arm on one shaft extending in a direction opposite that on the other shaft, a link having a lost motion connection between said crank arms for limiting the oscillation thereof, and means for taking up all lost motion or varying the extent thereof.

12. In marine propulsion mechanism, a hull, oscillatory shafts journaled therein, propeller vanes secured to said shafts and extending in the same direction therefrom,

a crank arm secured to each shaft, the crank arm on one shaft extending in a direction opposite that on the other shaft, a link connection between said crank arms comprising a lost motion section and an adjustable member connecting said lost motion section to the other crank arm.

13. In marine propulsion mechanism, a hull, oscillatory shafts mounted therein, propeller vanes secured to said shafts and extending in the same direction therefrom, a crank arm secured to each shaft, the crank arm on one shaft extending in a direction opposite that on the other shaft, a lost motion link connection between the said crank arms, said link connection comprising a pair of sections having lost motion connections with the crank arms, and a screw between said connections for taking up or varying the amount of lost motion.

14. In marine propulsion mechanism, a hull, shafts journaled perpendicularly in said hull, said shafts having their lower ends projecting below said hull, a propeller vane having one edge secured to the lower edge of each shaft, a lost motion link connection between said shafts for limiting their oscillations in each direction, a hoisting device and a flexible cable connecting each shaft to said hoisting device.

15. In marine propulsion mechanism, a hull, a shaft journaled perpendicularly therein, said shaft having one end projecting below the hull, means for limiting the oscillations of said shaft, a propeller vane having one edge secured to the lower end of said shaft, the sides of said vane converging from the shaft toward the free edge of the vane, the angle of convergence with respect to the central plane increasing from the top of said vane downward.

16. In marine propulsion mechanism, a hull, a shaft journaled perpendicularly therein, said shaft having one end projecting below the hull, means for limiting the oscillations of said shaft, a propeller vane having one edge secured to the lower end of said shaft, said vane tapering in width from top to bottom, the sides of said vane converging from the shaft toward the free edge of the vane, the angle of convergence with respect to the central plane increasing from the top downward.

17. An oscillating propeller vane adapted to oscillate about one edge, said vane tapering in width, and having sides converging toward the free edge, the angle of convergence with respect to the central plane increasing from the narrower to the wider end.

In testimony whereof I affix my signature.
JERRE McPHAIL BOWLES.
